UNITED STATES PATENT OFFICE.

JOHN B. LINTERN, OF CLEVELAND, OHIO.

SANDING DEVICE.

1,352,206.

Specification of Letters Patent. Patented Sept. 7, 1920.

Application filed January 29, 1920. Serial No. 354,969.

To all whom it may concern:

Be it known that I, JOHN B. LINTERN, a citizen of the United States, residing at Cleveland, in the county of Cuyahoga and State of Ohio, have invented a certain new and useful Improvement in Sanding Devices, of which the following is a full, clear, and exact description, reference being had to the accompanying drawings.

10 An object of this invention is to provide a simple, efficient and readily operable sanding device designed to release sand so that it may pass onto the trackway to enable a device rolling thereon to obtain proper traction. My sander is designed to be operated mechanically to release sand at the bottom of a receptacle allowing the desired quantity of it to descend by gravity for immediate application to the track, thereby insuring 15 good traction, notwithstanding grease, snow, or ice on the track, and thus increases efficiency and safety in operation.

20 More specific objects and features of my invention will be more fully hereinafter explained, and the essential characteristics thereof are summarized in the claims.

A preferred embodiment of my sanding device is illustrated in the drawings, wherein Figure 1 is a side elevation with parts of the receptacle broken away; Fig. 2 is a vertical section on the line 2—2 of Fig. 1; Fig. 3 is a similar section at right angles, showing the lower portion of the mechanism and taken on the line 3—3 of Fig. 2; Fig. 4 is a bottom plan of the device; and Figs. 5 and 6 are horizontal sections on the corresponding lines of Figs. 1 and 2.

Referring to the drawings, I have shown a sand receptacle 10 comprising a cylindrical body 11 having an annular flange 12 at one end and a removable lid or cover 13 fitted over the other end. Secured to the flange 12, as by bolts 14, is a bottom plate 15 having a central discharge opening or orifice 16. The edge of the orifice 16 is turned or swaged or otherwise treated to produce a downwardly extending annular lip, having a relatively sharp lower edge 17, constituting a valve seat. Above the lip 17 the edge of the orifice may be beveled as at 18.

A closure member for the orifice 16, comprising a valve adapted to coöperate with the valve seat 17, is provided in the form of

a circular plate 20 having an upwardly projecting rim 22 adapted to surround the sharp valve seat 17 when the plate proper abuts the edge thereof.

For supporting and guiding the valve plate 20, I have provided a rod 30 slidably received within the receptacle 10. A bearing plate 25 is spaced from the bottom plate 15 and supported thereby as by spacing sleeves 32 secured by bolts 31 passing upwardly through the bottom 15 and sleeves 32 and having their ends received in threaded engagement within openings in the plate 25. The plate 25 has a central opening surrounded by a sleeve 26 adapted to slidably embrace the rod 30.

The rod 30 is passed through a central opening 34 in the valve plate 20 and through a hollow boss 35 rigid with the plate 34. The upper portion of the rod is carried within the sleeve 26 of the plate 25 as a bearing, and projects for a distance above the plate 25. Between the plate 25 and the upper end of the rod 30 is a spring 37 compressed thereon and secured in position by a nut 38 on the threaded end of the rod. The nut 38 may be locked if desired, as by a set screw 39. A cap or casing 68 may rest on a shoulder 67 on the periphery of the plate 25 and constitute with the plate 25 an inclosing housing for the spring 37 and upper portion 85 of the rod 30.

The lower end of the rod 30 is preferably enlarged and bifurcated as at 40. A pin 42 carrying a roller 43 connects the lower ends of the furcations 40.

Secured to the bottom plate 15, preferably by the bolts 14 employed to secure this plate to the flange 12, is a funnel-shaped member comprising a casting 50 having a flanged upper end 51 with openings adapted to receive the bolts 14. The lower and smaller end of the member 50 may be internally threaded as at 52 to receive a hose or pipe to conduct sand to the track rail; neither the conduit nor the rail being shown.

Rigid with the member 50 and at opposite sides thereof are lugs 55 having openings constituting bearings for a shaft 57 extending through the member 50 and rotatably supported in said lugs. Rigidly secured to the rod 57, as by a pin 59 passing through a sleeve portion 61, is a tappet arm 62 adapted to be embraced by the furcations 40 at

the lower end of the rod 30. The tappet arm 62 is adapted to rest on the roller 43 carried by the pin 42. The shaft 57 projects outwardly through the funnel member 50 and carries rigidly on its end the hub 65 of a crank arm 63 with an eye 64 at one end adapted to be connected to a suitable operating member (not shown), whereby the shaft 57 may be oscillated whenever it is desired

10 to release sand.

Above the orifice 16 the rod 30 may carry rigidly secured thereto a spider 66, which is adapted to pass through the sand and loosen the same and insure its steady flow when the rod 30 is moved vertically.

15 In use the receptacle 10 is filled with sand which surrounds the casing 68 and fills the space between the supporting legs formed by the bolts 31 and sleeves 32. The valve plate 20 with its sleeve 35 resting on the enlarged lower end 40 of the rod 30, is held upwardly against the valve seat 17 under the tension of the spring 37, reacting between the bearing plate 25 and nut 38 on the upper end of the rod.

20 When it is desired to release sand onto the track, the shaft 57 is oscillated to move the tappet arm 62 downwardly and through the engagement of the latter with the roller 43 in the bifurcated end 40 of the rod 30, the latter is moved downwardly against the tension of the spring 37, thereby separating the valve plate 20 from its seat 17 and permitting the sand to flow by gravity downwardly through the orifice 16, around the periphery of the valve plate 20, and through the funnel 50 into the conduit below. Upon release of the shaft 57, the spring 37 immediately returns the rod 30 and valve plate 25 to its former position, the sharp edge 17 of the valve seat cutting through the sand above the valve plate, and permitting the latter to seat immediately with its flange 22 surrounding the edge 17, and shut off the flow of sand. This operation may be repeated whenever desired, the spider 66 agitating the sand and preventing its becoming caked above the orifice 16.

25 Having described my invention, I claim:

50 1. In a device of the character described, the combination of a receptacle having a discharge orifice, a member movable through the orifice, a closure for the orifice on said member below the orifice, means within the receptacle for urging the member upwardly, and means below the receptacle for moving the member downwardly.

55 2. In a device of the character described, the combination of a receptacle having a discharge orifice in the bottom thereof, a rod supported in bearings and movable vertically through said orifice, a closure member below said orifice on said rod, means within the receptacle for urging the rod and closure member upwardly to close the orifice, and

means below the receptacle for moving the rod and closure member in the opposite direction.

3. In a sanding device, a receptacle having an orifice, the edge of said orifice projecting 70 to form a sharp valve seat, a valve adapted to coöperate with said valve seat, and mechanical means below said valve for actuating said valve.

4. In a sanding device, a receptacle having 75 an orifice in the bottom thereof, the material around said orifice being turned downwardly to form a valve seat having a sharp edge, a recessed valve adapted to coöperate with said valve seat, and means for moving 80 said valve toward and away from said valve seat.

5. In a sanding device, a receptacle having an orifice therein, the edge of said orifice projecting downwardly into a thin edge constituting a valve seat, a valve plate below 85 said valve seat urged upwardly into engagement therewith, and mechanical means for drawing said valve plate downwardly.

6. In a sanding device, a receptacle having 90 a bottom plate with an orifice therein, the edge of said orifice projecting downwardly into a thin edge constituting a valve seat, a valve plate having an upstanding rim, spring pressed upwardly with the rim surrounding the valve seat, and means for moving 95 the valve plate downwardly.

7. In a sanding device, a receptacle having an orifice therein, a hollow member secured to the bottom of the receptacle around said 100 orifice, a rod movable through said orifice, a closure member for the orifice carried by said rod below the orifice, means for urging the rod upwardly, and means extending transversely through said hollow member 105 engaging said rod whereby it may be moved downwardly to open the orifice.

8. In a sanding device, a receptacle having an orifice in the bottom thereof, a conduit member secured to the receptacle around said 110 orifice, a bearing within said receptacle above said orifice, a rod slidable within said bearing, a valve carried by said rod below said orifice, means above said orifice for urging the rod and valve seat upwardly, 115 and means within said conduit member for moving said rod downwardly.

9. In a sanding device, a receptacle having an orifice in the bottom thereof, said orifice being constructed to form a valve 120 seat, a rod having a bearing above said orifice, and carrying a valve below said valve seat, said valve being urged toward said seat, the lower end of said rod being slotted, 125 a shaft mounted transversely of said receptacle, means secured thereto engaging said slot, and means for oscillating said shaft whereby said rod and valve may be moved downwardly.

10. In a sanding device, a receptacle hav- 130

ing an orifice in the bottom thereof, a funnel-shaped member surrounding said orifice below the receptacle, a rod movable through said orifice, a closure member on the rod 5 below the orifice, means for urging said rod upwardly to close the orifice, and means in said funnel-shaped member in pivotal engagement with said rod to move the latter downwardly.

10 11. In a sanding device, a receptacle having an orifice in the bottom thereof, a hollow member surrounding said orifice below the receptacle, a rod having a bearing within said receptacle and slideable vertically through said orifice, said rod having an enlarged slotted lower end, a closure member for said orifice resting on said enlarged end, means for urging said rod and closure member upwardly and oscillatable means in 15 said hollow member engaging said slotted end to move said rod and closure member downwardly.

12. In a sanding device, a receptacle having an orifice in the bottom thereof, a hollow member surrounding said orifice below said receptacle, said orifice being constructed to form a valve seat, a rod having a bearing above said orifice, and carrying a valve plate below said valve seat, means 20 above said bearing urging said rod and valve upwardly, a slot in the lower end of said rod, a shaft mounted transversely of said hollow member, means on said shaft engaging said slot, and means for oscillating said shaft whereby said rod and valve may be 25 moved downwardly.

13. In a sanding device, a receptacle having an orifice in the bottom thereof, constituting a valve seat, a rod extending through said orifice into said receptacle and below the same, a bearing for said rod within said receptacle, a spring for urging it upwardly into the receptacle, a valve carried by said rod below said orifice and closing the same when said rod is in its uppermost position, a shaft mounted transversely below said receptacle, and a pivotal connection between said shaft and said rod whereby oscillation of the former may move 40 the latter and said closure member downwardly to open said orifice.

14. In a sanding device, a receptacle having an orifice in the bottom thereof, a hollow member secured to the bottom of said receptacle around said orifice, a rod extending through said orifice into said receptacle and said hollow member, a bearing for said rod within said receptacle, a spring for urging the rod upwardly into the receptacle, 45 a closure member for said orifice carried by said rod and in operative position when said rod is in its uppermost position, a shaft mounted transversely within said hollow member, and a pivotal connection between 50 said shaft and said rod whereby oscillation

of the former may move the latter and said closure member downwardly to open said orifice.

15. In a sanding device, comprising a receptacle having an orifice in the bottom thereof, a rod movable through the orifice and urged upwardly, a closure member secured to the rod near its lower end and below the orifice, said lower end being bifurcated, a shaft mounted transversely of said rod below said receptacle, a tappet arm on said shaft embraced by the furcations of said rod, a pin connecting said furcations on which said tappet arm rests, and means for oscillating said shaft and tappet arm 70 downwardly to move said rod and closure member upwardly against the tension of said spring.

16. In a sanding device, comprising a receptacle having an orifice in the bottom thereof, a bearing plate supported in spaced relation above said orifice, a rod slideable within said bearing plate and projecting downwardly through the orifice and above said bearing plate, a spring around the upper end of said rod compressed between said bearing plate and means on the end of the rod, a cover secured to said bearing plate inclosing said spring and the upper end of said rod, a closure member for said orifice 85 secured to the rod near its lower end, and means for moving said rod and closure member upwardly against the tension of said spring.

17. In a sanding device, a discharge opening in the bottom thereof, a valve below the opening for controlling said opening, a rod supporting said valve and extending upwardly through said orifice into said receptacle, a bearing for said rod, means for securing said bearing plate spaced from the bottom of said receptacle, said rod projecting upwardly above said bearing plate, means above said bearing plate for urging the rod upwardly, means on said rod between said bearing plate and orifice for 100 loosening the sand within said receptacle above the orifice, and means for moving said rod downwardly.

18. In a sanding device, a discharge opening in the bottom thereof, a valve below said opening movable bodily toward and away from said opening, a rod supporting said valve and extending upwardly through said orifice into said receptacle, a bearing for said rod comprising a plate having a central opening and a sleeve rigid therewith surrounding said rod, means for securing said bearing plate spaced from the bottom of said receptacle, said rod projecting upwardly above said bearing plate, a nut secured to the end thereof, a helical spring surrounding said rod between the nut and bearing plate, a cap secured to said bearing plate inclosing the upper end of said rod and spring, and means on said rod between 115 120 125 130

said bearing plate and orifice for loosening the sand within said receptacle above the orifice, and means for moving said rod and closure means downwardly to open the discharge opening.

19. A sanding device comprising a receptacle having a cylindrical wall having an annular flange at one end, a bottom plate having an opening and secured to said flange, a conduit member secured to said plate and first mentioned flange, a housing within said receptacle above the opening in said plate, a rod slidable within a bearing in said housing and extending downwardly through said opening, a closure member on said rod below said opening, means within said housing for urging said rod upwardly, a shaft mounted transversely of said rod and extending through said conduit member, a tappet arm secured to said shaft and pivotally engaging said rod, and means for oscillating said shaft to cause said tappet arm to move said rod downwardly.

20. A sanding device comprising a receptacle having a cylindrical wall having an annular flange at one end, a plate having a central opening and secured to said flange,

a funnel-shaped member having a flange secured to said plate and first mentioned flange, a housing within said receptacle 30 spaced above the opening in said plate, a rod slidable within said housing and extending downwardly through said opening, the lower end of said rod being bifurcated, a pin connecting the lower portions of said 35 bifurcations, a roller on said pin, a shaft mounted transversely of said rod and extending through said funnel-shaped member supported in bearing lugs secured thereto, a tappet arm secured to said shaft and 40 embraced by said bifurcations, said tappet arm resting on said roller, a closure member on said rod above said bifurcations, means within said housing for urging said rod upwardly with said closure member engaging 45 the opening in said plate, and means for oscillating said shaft to cause said tappet arm to move said rod downwardly, thereby separating said closure member from said plate. 50

In testimony whereof, I hereunto affix my signature.

JOHN B. LINTERN.
